FIG. 1 is a perspective view of a cover for a container, showing a new design, and shown in extended view with its environment.

FIG. 2 is a top perspective view thereof.

FIG. 3 is a bottom perspective view thereof, opposite the view shown in FIG. 2.

FIG. 4 is a front view thereof;

FIG. 5 is a rear view thereof;

FIG. 6 is a left side view thereof;

FIG. 7 is a right side view thereof;

FIG. 8 is a top view of thereof; and,

FIG. 9 is a bottom view thereof, opposite the view shown in FIG. 8.

The broken lines shown herein depict environment only and form no part of the claimed design.
